(57) **CLAIM**

The ornamental design for a mobile phone, as shown and described.

DESCRIPTION

FIG. 1 is a front elevation view of a first embodiment of a mobile phone showing our new design;
FIG. 2 is a rear elevation view thereof;
FIG. 3 is a left side elevation view thereof;
FIG. 4 is a right side elevation view thereof;
FIG. 5 is a top plan view thereof;
FIG. 6 is a bottom plan view thereof;
FIG. 7 is a front perspective view thereof;
FIG. 8 is a rear perspective view thereof;
FIG. 9 is a front elevation view of a second embodiment of a mobile phone showing our new design with the front camera activated;
FIG. 10 is a rear elevation view thereof;
FIG. 11 is a left side elevation view thereof;
FIG. 12 is a right side elevation view thereof;
FIG. 13 is a top plan view thereof;
FIG. 14 is a bottom plan view thereof;
FIG. 15 is a front perspective view thereof;
FIG. 16 is a rear perspective view thereof;
FIG. 17 is another front perspective view of the mobile phone of FIG. 9 shown with the camera deactivated;
FIG. 18 is a front elevation view of a third embodiment of a mobile phone showing our new design with the front camera activated;
FIG. 19 is a rear elevation view thereof;
FIG. 20 is a left side elevation view thereof;
FIG. 21 is a right side elevation view thereof;
FIG. 22 is a top plan view thereof;
FIG. 23 is a bottom plan view thereof;
FIG. 24 is a front perspective view thereof;
FIG. 25 is a rear perspective view thereof; and,
FIG. 26 is another front perspective view of the mobile phone of FIG. 18 shown with the camera deactivated.
